BRASSIÈRE

Ben Frommer, Toronto, Ontario, Canada, assignor to Rose Marx Brassieres Ltd., Toronto, Ontario, Canada, a corporation of Canada

Application May 24, 1949, Serial No. 95,125

3 Claims. (Cl. 2—42)

1

This invention comprehends improvements in brassières of the uplift type.

One object of the invention contemplates the provision of an improved brassière which will provide the optimum of support for the breasts; another object: a brassière which has formed therein a uniquely pointed contour, totally devoid of sags, ripples, centrally of each breast pocket section, embracing the natural contour of the breasts and providing a non-irritating snug receptacle for the breast nipples. A further object is the provision of novel means for producing the said pointed contour. The brassière further maintains the natural and desired contours of the breast, and enhances the appearance and feeling of the figure.

Briefly described, the brassière comprises two pointed breast pocket sections, each having a French, or overlapping seam, running vertically and medially thereof from top to bottom, said seam being relatively oppositely disposed and adjacent the interior wall from the top of the breast section to the midpoint thereof, as compared with the disposition of said seam from the midpoint to the top of the band therebelow. As the French seam crosses over, or changes its disposition from one side to the other on the inside of the brassière, there is formed a snug, non-irritating receptacle for the nipple and at the same time such change of disposition, as it is caused to occur at the apex of the point of the cup, assists in the sustaining and maintenance of the point of the contour of the breast section. Straps run from the top of each breast section to the rear of the waistband, the latter encircling the waist and having at their opposite ends eyelets and lacing for tightening and holding the brassière in comfortable, supporting position. The brassière is susceptible of modification and one such modification is illustrated hereinafter.

In the drawings:

Fig. 1 illustrates collectively the general shape or pattern of the material prior to the assembly into the complete brassière as shown in Figs. 5 and 6.

Fig. 2 depicts the two blanks of material forming one of the breast pocket sections, with the first seam stitched along a marginal edge.

Fig. 3 shows the same two blanks inverted with the French seam capturing or enclosing the outer seam.

Fig. 4 a sectional view along lines 4—4 of Fig. 3 showing the construction of the seam.

Fig. 5 a rear view of assembled brassière from

2

the inside showing the twisted French seam and illustrating how its upper and lower extremities are attached and turned at the binding and band, respectively.

5 Fig. 6 a front perspective view of the bra shown worn.

Fig. 7 a fragmentary side view showing the desired uplifting form of the bra.

Fig. 8 a front view of the modification.

10 Fig. 9 a rear view thereof.

In the drawings like numerals are given for like parts.

15 With reference particularly to Fig. 1, the blanks of material 6, 7 are preferably cut lengthwise of the material, and these blanks, with the right or finished side of the material out are stitched along their adjacent marginal edges, as at 8. The two parts, as assembled, are then turned inside out or inverted, and the overlapping seam 9 is then stitched, enclosing the previously formed seam 8, forming flange or French seam 10.

20 The companion blanks 6, 7 for the other breast pocket section are similarly formed, and these sections I shall refer to by the numeral 11, with 5 referring to the entire bra.

25 In fabricating my brassière, in attaching binding 12, and straps 13, as by stitching at 14, I turn and attach the upper portion of French seam 10 inwardly, for example, with the seam turned toward the center, and, when the breast pocket section 11 is stitched to the band 15 as by stitching at 16, I invert the French seam 10 in the opposite direction, and it is stitched with it facing away from the center, shown in Fig. 5.

30 Conventional darts 17 are provided, the breast pocket sections 11 are stitched together as at 18, and straps 13 attached to the rear of band at 19.

35 40 On the opposite free ends of band 15 I provide eyelets 20 and lacing 21.

45 As admirably shown in Fig. 5, French seams 10 are disposed or turned toward the inside or center of the brassière from the top of the breast pocket section to approximately the center point or tip 22 thereof, then seams 10 turn over, cross, or twist and extend in the opposite direction from tips 22 to the band 15, at the bottom. The flap portion of the seam lies adjacent the inner wall of breast pocket sections 11 both above and below the point at which it turns over, crosses, or twists.

50 55 The turning point of seam 10 obviates any protruding or deformation of the natural beauty

because of the twisting in opposite direction of the French seam 10.

From the standpoint of the outer contour of the breast pocket section, the turning or twisting point of the seam 10, from one side toward the other is instrumental in maintaining the apex or peak of the said contour which conforms to a nicety with the configuration of the breasts, sustains and supports them. Additionally, the French seam 10 in itself is a supporting feature for the breast pocket section, precluding any tendency to sag or ripple. And, as depicted in Fig. 6, exteriorly of the breast pocket sections, only a single stitching line of seam 9 appears, adding to the aesthetic qualities of the brassière.

It should be understood that the seam 10 may be attached to the binding 12 and band 15 in the reverse of the arrangement shown in Fig. 4 in which case the seam would be turned away from, instead of toward the center, at the binding 12, and oppositely, or toward the center at band 15.

In the modification shown in Figs. 7 and 8, I provide a wider band 23 and breast pocket sections 24, and blanks or panels 25, attached to the waist-band in the rear and to the sides of the breast pocket sections 24, forming an added support for the breast pockets.

In wearing the brassière lacing 21 is tightened until band 15 comfortably embraces the midriff, and the brassière, when positioned, affords the maximum of comfort; supports and enhances the natural contours of the breast, and besides its aesthetic superiority, has had the endorsement and recommendation of medical doctors who state that the snug, non-irritating pocket for the nipples, the absence of boning or of any construction, precludes irritation which often leads to serious diseases of the breast.

The brassière may be manufactured from "nylon," rayon satin, cotton, broadcloth, cotton lace, or any other suitable material; binding 12 may be embellished by lacing; and I reserve the right to make such other changes or modifications as may come within the scope of the appended claims.

I claim:

1. A brassière including: joined breast pocket sections each comprising two blanks of material attached vertically and medially by a French seam to form breast-supports having pointed contours, and having interior and exterior pocket walls; binding at the top of said breast pocket sections holding the flanges of the upper extremities of the French seams flat against the interior walls of the breast pocket sections bent away from the center of the joined breast pocket sections; a band joined to the lower edges of the

breast pocket sections holding the flanges of the lower extremities of the French seam against the interior walls of the breast pocket sections bent toward the center of the breast pocket sections; the extending flanges of the French seam lying relatively flat against the interior walls and bent away from the center of joined breast pocket sections from the top thereof downward to the apex of the pointed contour, said flanges then inverting at the apex and lying relatively flat against the interior walls turned toward the center of the breast pocket sections downward to the bottom thereof whereby a non-irritating, snug receptacle for the breast is formed by the apices of the pointed contours; straps attached to the tops of the breast pocket sections and to the rear of the band; and means to adjustably fasten the said band at the free ends thereof.

2. A brassière including: joined breast pocket sections each comprising two blanks of material attached vertically and medially by an overlapping seam to form breast supports having pointed contours and having interior and exterior pocket walls; binding at the top of said breast pocket sections holding the flanges of the upper extremities of the overlapping seam flat against the interior walls of the breast pocket sections bent toward the center of the joined breast pocket sections; a band having free ends joined to the lower edges of the breast pocket sections holding the flanges of the lower extremities of the overlapping seam against the interior walls of the breast pocket sections bent away from the center of the two said sections; the flanges of the overlapping seam disposed away from the center inverting to the oppositely extending direction at the apices of the said pointed contours whereby said apices form a non-irritating, snug receptacle for the breast; straps attached to the tops of the breast pocket sections and to the rear of the band; means for adjustably connecting the free ends of the bands.

3. A brassière for supporting the breasts as recited in claim 2 wherein the point of inversion of the French seam provides a relatively free non-irritating space for the reception of the breast portions contiguous thereto and there is also provided a pointed contour devoid of sags and ripples.

BEN FROMMER.
